UNITED STATES PATENT OFFICE

155,684

DESIGN FOR A COMBINED SURFACE LEVEL AND ADVERTISING DEVICE

Clarence E. Crawford, Flint, Mich., assignor of
one-half to Clayton C. D. French

Application October 27, 1947, Serial No. 142,156

Term of patent 14 years

(Cl. D52—1)

To all whom it may concern:

Be it known that I, Clarence E. Crawford, a citizen of the United States, residing at Flint, in the county of Genesee and State of Michigan, have invented a new, original, and ornamental Design for a Combined Surface Level and Advertising Device, of which the following is a specification, reference being had to the accompanying drawing, forming part thereof.

Figure 1 is a perspective view of a combined surface level and advertising device embodying my new design.

Figure 2 is a side elevation of the combined surface level and advertising device shown in Figure 1, the end elevation being the same.

I claim:

The ornamental design for a combined surface level and advertising device, substantially as shown.

CLARENCE E. CRAWFORD.
